UNITED STATES PATENT OFFICE.

CHARLES A. BARRON, OF WOODLEY, NEAR STOCKPORT, ENGLAND.

CONTINUOUS-WIRE-DRAWING MACHINE.

1,316,935.

Specification of Letters Patent. Patented Sept. 23, 1919.

Application filed September 14, 1918. Serial No. 254,079.

To all whom it may concern:

Be it known that I, CHARLES ARNOLD BARRON, a subject of King George V of Great Britain, residing at Woodley, near 5 Stockport, in the county of Cheshire, England, have invented a new and useful Improvement in Continuous-Wire-Drawing Machines, of which the following is a specification.

10 This invention relates to wire drawing machines in which the wire passes in succession through a series of dies and around respective draw drums to elongate or draw it to the degree of fineness desired, and the 15 object of my improvements is to provide simple and effective means for controlling the speeds of the winding drums according to the diameter of the finishing block upon which the drawn wire is finally wound and 20 means applied in conjunction with each drawing head for controlling the speed of the respective draw drum according to the elongation of the wire being wound thereon, such improved means, while applicable to 25 machines for drawing various thicknesses of wire, being especially advantageous in the drawing of very fine wire.

The object and nature of the invention thus set forth will appear more fully from 30 the accompanying description and drawing and will be particularly pointed out in the claims.

Figure 1 is an end elevation, looking in the direction of arrow A (Fig. 2) of a wire 35 drawing machine embodying my improvements and showing more particularly the application of such improvements to the winding drum or blocks at the finishing end of the machine, the cross shaft for the near 40 draw drums being broken away;

Fig. 2 is an elevation of a portion of one side of the machine showing more particularly the application of my improvements to the individual draw drums, and 45

Fig. 3 is a transverse section taken on line B, C of Fig. 2.

Referring to the drawings, and firstly to Fig. 1, letter *a* represents the usual finishing blocks upon which the drawn wire is 50 finally wound, there being one block for receiving the wire drawn by the series of draw drums on each longitudinal side of the machine. If only one side of the machine is fitted with draw drums, one finishing block 55 only is employed. The said blocks *a* are mounted on vertical spindles *b* supported

in bearings *c* bolted to or forming a part of the framework *d* of the machine.

According to the invention, rotary motion is transmitted to each block *a* through bevel pinion *e* and bevel wheel *e'* from a counter shaft *f* having mounted thereon two differential motions, one for each block *a*, each differential motion comprising a driven toothed or sprocket wheel *g* loosely mounted 60 on a sleeve *h* which is in turn loosely mounted upon the counter shaft *f*. The said sleeve *h* has fast on one end thereof a grooved brake or like pulley *i* and on its opposite end a toothed wheel *j* which meshes with planet 65 pinions *k* mounted loosely on studs *l* secured to the driven toothed wheel *g*. Each toothed wheel *g* is positively driven in this instance by chain *m* from sprocket wheels *n* fast on a shaft *o* receiving motion from the main 70 shaft of the machine.

The planet pinions *k*, of which there may be three or other desired number, mesh with an internal toothed ring *p* concentric with the toothed wheel *j* and secured by screws 80 or like means to or formed integral with a disk *q* the boss of which is mounted on and keyed or otherwise secured to the boss of the bevel pinion *e*.

Normally the parts comprising each differential revolve as one piece, the internal toothed ring *p* thereof being carried around at the same speed as the toothed wheel *g* by spring pressed pawls or fingers such as *r* (see Fig. 2) pivotally mounted on studs secured to the driven toothed wheel *g*, this being a common feature in differential motions and, *per se*, forming no part of my invention.

By applying pressure to the brake drum 95 or pulley of each or either of the differentials as by a strap, or as in the instance illustrated, by the end of a screwed spindle *s* working through a nut *s'* in a cross girt, the speed of rotation of the toothed gear *j* 100 can be retarded to any desired extent according to the adjustment of the screwed spindle *s*, and such retardation of the speed of gear *j*, through the action of the planet pinions *k* causes the toothed ring *p* and the 105 disk *q* secured thereto to be driven at a correspondingly accelerated speed. The degree of acceleration is determined by the diameter of the finishing block *a* employed and is adjusted before the starting of the machine, 110 such means of varying the speed of rotation of the finishing blocks enabling varying

diameters of such blocks within given limits to be employed in the machine and interchanged one for another as required without affecting the operation of the machine, the 5 speed at which each finishing block is driven controlling the speed of each individual drawing drum in the machine.

Referring now more particularly to Figs. 2 and 3, I provide in conjunction with means 10 for determining the speed of rotation of the finishing block for a series of drawing drums, means comprising similar differential motions for self-actingly adjusting or controlling the speed of each individual 15 drawing drum in the several drawing heads according to variations from the normal in the elongation of the wire.

The parts comprising the differential combined with each draw drum t , or drawing 20 head, of which there may be any suitable number arranged at suitable distances apart side by side longitudinally on both sides of the machine, bear the same letters of reference as the corresponding parts of the differentials already described with reference 25 to the finishing blocks a but in this instance, the toothed wheels g' are conveniently geared together by intermediate or carrier pinions u and motion is transmitted to same 30 in any appropriate manner from the main shaft of the machine. The disks q' carrying the internal toothed rings p' are in this instance secured to or formed integral with the draw drums t . With the exceptions 35 noted, the description previously given of the differentials for the finishing blocks applies also to the differentials for each draw drum and need not therefore be again set forth.

40 In a suitable position adjacent to and preferably below each brake or grooved pulley i secured to the sleeves h carrying the individual differentials, is pivoted on a stud v secured to the framing of the machine, or to 45 a bracket, a two armed lever w suitably weighted at one end w' and carrying at the opposite end a grooved pulley w^2 . Two separate arms pivoted on the said stud v could be employed in lieu of a single double 50 armed lever.

The wire x is fed through to the die y in the die block y' preceding each draw drum in the usual manner and after leaving the die is passed around the respective draw drum t 55 but instead of being coiled around said drum in the ordinary manner it is passed intermediately around the grooved pulley w^2 on the respective weighted lever w and then passes again around the draw drum on its 60 way to the next succeeding die, the procedure being continued in respect of each following draw drum until the wire is finally wound upon the finishing block a , each succeeding drawing operation between the die and next 65 draw drum reducing the diameter of the wire

until the desired reduction is obtained at the last drawing head.

Each lever w has connected at a suitable point thereto, one end of a brake strap z which extends around the brake drum or 70 pulley i and is secured at its opposite end in any suitable manner to a fixed part such as a boss or collar on the stud v or on the lever w .

If the elongation of the wire at each drawing head is normal, each differential and its winding or draw drum t rotate as one piece at the normal speed, but immediately the elongation of the wire at any one or more drawing head becomes abnormal, that is to say, the wire is not being fed to the draw drum at the same rate of speed as the surface speed of said drum, the pull of the wire passing around the grooved pulley w^2 caused by its reduced rate of feed through the die y 85 to the drum, rocks the lever w to a corresponding extent whereby the brake strap z is drawn more or less tightly around the brake pulley i and the speed of the draw drum t through the action of the differential 90 in the manner above described with reference to the finishing blocks a , is accelerated, such acceleration of motion continuing until the elongation of the wire becomes normal again when the brake strap is slackened by the 95 movement of the lever w to its original position under the action of the balance weight w' and the draw drum is again caused to revolve at the same speed as the driven toothed wheel g .

The speed of each drawing drum is thus individually and self-actingly controlled according to the degree of elongation of the wire through each die, and slipping of the wire around the draw drum is prevented.

The range of speed of each differential may be varied by varying the number of teeth in the gear wheels or by increasing the number of gears, and other types of gears could be employed in place of those shown, 110 the construction being modified to suit the form of gears used.

Having thus described my invention, what I claim as new and desire to secure by Letters Patent is:—

1. In a wire drawing machine, a revolute finishing block, a differential driving mechanism operatively connected with the said finishing block, means for driving one member of the differential mechanism positively, 120 a brake connected with another member of the differential mechanism, and means for adjusting the action of the brake so as to vary the speed of the finishing block through the instrumentality of the said differential 125 mechanism.

2. In a wire drawing machine, a driving shaft for a finishing block, a finishing block for receiving the fully drawn wire mounted removably on the said shaft so that finishing 130

blocks of different size can be substituted for it, a driving wheel operatively connected with the said shaft, a positively driven driving wheel, a differential gearing interposed 5 between the two said driving wheels, a brake wheel operatively connected with one member of the differential gearing, and a manually adjustable device for applying pressure to the said brake wheel and thereby accelerating the speed of the driving shaft and finishing block to suit the size of the finishing block.

3. In a wire drawing machine, a vertical driving shaft for a finishing block, a finishing block for receiving the fully drawn wire mounted removably on the said shaft, a horizontal driving shaft, bevel toothed wheels operatively connecting the two said shafts, a positively driven driving wheel mounted 10 concentric with the said horizontal shaft, a differential gearing interposed between the said driving wheel and one of the beveled toothed wheels, a brake wheel operatively connected with one member of the differential gearing, 15 and means for applying pressure to the

brake wheel to accelerate the speed of the finishing block.

4. In a wire drawing machine, a revoluble draw drum, a die block preceding the said draw drum, a positively driven driving wheel 20 journaled concentric with the draw drum, a differential mechanism interposed between the said driving wheel and draw drum, a brake wheel operatively connected with one member of the differential mechanism, a piv- 25 oted lever provided with means for retarding the motion of the brake wheel, and a roller carried by the said lever and adapted to have the wire looped over it in its passage around the said draw drum, whereby 30 the speed of the said draw drum is controlled by the action of the said preceding die block on the wire.

In testimony whereof I affix my signature in the presence of two witnesses.

CHARLES A. BARRON.
